UNITED STATES PATENT OFFICE

123,113

DESIGN FOR A LAWN MOWER HANDLE

Stanley D. Loud and William E. Sullivan,
Worcester, Mass., assignors to Worcester Lawn
Mower Company, Worcester, Mass., a corpora-
tion of Massachusetts

Application February 3, 1940, Serial No. 89,972

Term of patent 14 years

To all whom it may concern:

Be it known that we, Stanley D. Loud and Wil-
liam E. Sullivan, both citizens of the United
States, residing at Worcester, in the county of
Worcester and Commonwealth of Massachusetts,
have invented a new, original, and ornamental
Design for a Lawn Mower Handle, of which the
following is a specification, reference being had
to the accompanying drawing, forming part
thereof, in which

Figs. 1 and 2 are a front view and a side view,
respectively, of a lawn mower handle embodying
our new design.

Fig. 3 is a larger scale sectional view on the
line 3—3 of Fig. 1.

We claim:

The ornamental design of a lawn mower
handle, as shown.

STANLEY D. LOUD.
WILLIAM E. SULLIVAN.
